UNITED STATES PATENT OFFICE.

PAUL S. QUAST, OF LOS ANGELES, CALIFORNIA.

PROCESS OF MAINTAINING HAIR IN POSITION.

No Drawing.

Application filed October 23, 1924. Serial No. 745,523.

To all whom it may concern:

Be it known that I, PAUL S. QUAST, a citizen of the United States, residing at Los Angeles, in the county of Los Angeles 5 and State of California, have invented a new and useful Process of Maintaining Hair in Position, of which the following is a specification.

This invention relates to processes according to which hair may be treated to prevent it from shifting or moving lengthwise when disposed or mounted within or in relation to some other material for commercial use.

One of the objects of this invention is to 15 treat hair so as to prevent it from shifting or moving within so-called hair-cloth as used in clothing.

Another object is to treat hair so that it may be maintained in a certain position so 20 that it will not shift or move after once placed in such a position.

Other objects will appear from the following description and appended claims.

Hair-cloth, above referred to, is commonly 25 used in all kinds of clothing as a padding or reinforcement or for otherwise facilitating a desired shaping of clothing.

It is, however, well known that hair tends to shift or move within clothing and eventually 30 work itself out of hair-cloth inserted in such clothing. While moving out of clothing, hair tends to irritate the body on which such clothing is worn and is therefore to some extent disagreeable to the 35 wearer of the clothing.

I am aware of the fact that hair-cloth is being used and commonly available on the market of different grades and qualities, and that the better qualities are less liable to 40 allow or cause a loss of hair than the inferior qualities. However, some hair will remove or move out.

To prevent a moving or shifting of hair when disposed in clothing, that is commonly 45 within hair-cloth disposed or mounted within clothing, this invention has for its principal feature a process or method of dulling the hair-ends so that the hair is practically dispossessed of its ability to penetrate clothing. By experiments it has been found that 50 one way of accomplishing this result is by burning or singeing the ends of the hair. This can easily be accomplished by first cutting hair-cloth to a certain desired shape in 55 which it is to be used in clothing and then burning or singeing the edges of such a cut

or shaped piece of hair-cloth and thereby burning or singeing the ends protruding from such edges of the hair-cloth. When so treated the hair-cloth is merely placed 60 at the proper point within the clothing and sewed in in the usual manner.

Hair so treated and mounted within clothing is practically made non-shiftable or non-movable so that the disagreeable protruding 65 of hair-ends from clothing may be prevented.

Of course, hair is used in many different articles for many different purposes and mounted in various forms and holders, as 70 in brushes, but it will easily be understood that, by a singeing or burning of the hair-ends before being mounted in a certain holder the hair will be more firmly held in any holder or other mounting.

The hair-ends may also be dulled by other treatments, as by being held in bunches and then subjected to blows or strokes at its ends.

The main reason that hair is so easily 80 worked out from some qualities of hair-cloth may be said to be that it is practically impossible to cut hair with scissors squarely to its longitudinal axis since hair tends to slip out from between the cutting edges of 85 scissors and at the moment of being finally cut, such hair may be said to have come to an inclined position in relation to the cutting edges of the scissors so that the hair is actually cut with sharp points at its ends 90 instead of squarely.

Another slightly modified form of treating hair according to this invention is therefore to produce dull ends when severing or cutting hair whether in hair-cloth or mounted or in conjunction with other material. Hair may be held firmly and close to the point where a cut is to be made before actually being cut so as to assure a square cut.

Whether burned, or singed, or subjected 100 to blows on the ends, or otherwise similarly treated, the principal point of this invention is to produce dull ends on hair.

Having thus described my invention, I 105 claim:

1. The process of treating hair which consists in mounting the hair, and enlarging the hair-ends protruding from the mounting for holding the hair against lengthwise shifting when embedded in a holding medium.

2. The process of treating hair which consists in mounting the hair, and singeing or

burning the hair-ends protruding from the mounting so as to form enlarged terminations for holding the hair against lengthwise shifting.

5. The process of treating hair which consists in mounting the hair, cutting the hair a short distance beyond the mounting, and then enlarging the ends of the hair protruding from the mounting for holding the hair 10 against lengthwise shifting.

4. The process of treating hair cloth which consists in cutting the cloth to a desired form and then enlarging the ends of the hair protruding from the edges of the 15 cloth for holding the hair in the cloth against lengthwise shifting.

5. The process of treating hair-cloth to be used in clothing which consists in cutting the cloth to a desired shape, then singeing the edges of the cloth and thereby the 20 ends of the hair protruding from the edges of the cloth.

6. The process of making clothing which consists in producing certain pieces of hair-cloth of desired shape, then singeing the 25 edges of the shaped cloth and thereby the ends of the hair protruding from its edges, and then mounting this shaped and treated hair-cloth within clothing.

In testimony that I claim the foregoing 30 as my invention I have signed my name.

PAUL S. QUAST.
